UNITED STATES PATENT OFFICE.

JOHN ENRIGHT, OF LOUISVILLE, KENTUCKY, ASSIGNOR TO HIMSELF,
WILLIAM WALL, AND THOMAS ENRIGHT, OF SAME PLACE.

IMPROVEMENT IN CORE-BARS FOR CASTING PIPE.

Specification forming part of Letters Patent No. 104,397, dated June 14, 1870.

To all whom it may concern:

Be it known that I, JOHN ENRIGHT, of Louisville, in the county of Jefferson and State of Kentucky, have invented a new and useful Improvement in Core-Bars for Casting Pipes; and I do hereby declare that the following is a full, clear, and exact description of the same, reference being had to the accompanying drawing, making a part of this specification, in which—

Figure 1 is a sectional elevation; Fig. 2, a transverse vertical section.

This invention relates to a core-bar that may be made to collapse after a pipe has been cast around it, in order that the bar may be readily withdrawn from within the pipe, and that may be expanded again to the required size previous to being inserted in the mold, whereby the use of hay-rope or other elastic body wound around the core-bar, to be afterward burned in order to permit the withdrawal of the core-bar, is rendered unnecessary, and a metallic surface presented for the loam coating to be placed upon.

In the drawing, *a a a a* are four separate curved plates, which, together, form a complete cylinder. *b* are prongs projecting inwardly from each of the plates *a*, and having inclined lower sides. *e* is a bar placed centrally within the plates *a*. *d* are prongs projecting outwardly from four sides of the bar *c* beneath the prongs *b*, and having inclined upper and lower sides. *e* is a collar placed loosely outside the central bar *c*, near its upper end. *f f* are equalizers, pivoted one to each side of the collar *e*. *h* are links which connect the upper prongs *b* of the plate *a* with the ends of the equalizers *f*, there being one link to each plate *a*, and two of said plates being by the links *h* connected with each equalizer. *i* are prongs with inclined upper surfaces, projecting inwardly from the four plates *a* beneath the prongs *d* of the central bar. *k* is a key by which the collar *e* and bar *c* may be connected by passing it through orifices made for the purpose in each.

The core-bar, formed of the plates *a*, is expanded, when the plates are suspended by hooks *l* passed under the equalizers, and connected by chains *m* with a shackle, *n*, that is

attached to the arm of a crane by letting the central bar *c* drop in the collar *e* until the pin *o*, which passes through the head of the bars *c* and enters slot *r* cut in the sides of the shackle *n*, brings up against the bottom of said slots and arrests the further descent of the bar. This descent brings the inclined sides of the prongs *d* of the bar against the inclined sides of the prongs *i* of the plates, and consequently forces the latter outward. In this expanded condition the core-bar is placed in the mold after being coated with loam and the pipe is poured around it. When the time comes for removing the core-bar from the pipe, the key *k* is withdrawn from the orifice of the bar, and remains only in the collar *e*, being held there by a lip on the latter fitting into a groove in the outside of the key, and by means of the crane the bar *c* is raised in the collar *e* and brings the upper inclined sides of the prongs *d* against the lower inclined sides of the prongs *b*, by which movement the plates *a* are drawn inward, and the core-bar made to collapse, and after collapsing they rise, hanging on the prongs thus.

The immediate means of elevating the bar *c* are the bent arms of the lever *s*, which is pivoted to the outside of the shackle *n* and turned so as to bring its arms under the pin *o*. During the elevation of the bar *c* the hooks *l* are beneath the equalizers *f*. When in this elevated position the core-bar is to be expanded again, the lever *s* is turned so as to withdraw its arms from beneath the pin *o*, whereupon the bar *c* drops, as before described. The key *k* is then anew inserted, and the core-bar is once more ready to be placed in the mold. The upper sides of all the prongs are made of inverted V-shape in order to shed particles of molten metal.

The function of the equalizers *f* is, as their name imports, to equalize the pressure of the prongs of the bar upon the prongs of the plates *a*.

Instead of the links *h*, the equalizers *f* may be extended downward far enough to connect directly with the upper prongs, *b*, slots being made in the latter to admit of the necessary play of the plates *a*.

Instead of shackle *n*, I may prefer to make

use of hooks attached to the gibbs of the crane and placed under the equalizers when the core-bar is elevated. I consider the shackle, however, to be the better arrangement.

In addition to the prongs *d* on the central bar, two of which on each side are sufficient, I add prongs *t*, having recesses in their lower sides, the use of which is to support the plates *a* against external pressure.

Having thus described my invention, what I claim as new, and desire to secure by Letters Patent, is—

1. The prongs *d* of the central bar *c*, in com-

bination with the prongs *b i* of the plates *a*, when constructed and operating substantially in the manner described.

2. The equalizers *f*, combined with the collar *e* and plates *a*, in the manner and for the purpose specified.

3. The bar *c*, combined with the slotted shackle *n* and lever *s*, in the manner and for the object specified.

JOHN ENRIGHT.
